(57) CLAIM

The ornamental design for a support structure for a grill, as shown and described.

DESCRIPTION

FIG. 1 is an upper perspective view of a support structure for a grill showing my new design;

FIG. 2 is a front elevation view thereof;

FIG. 3 is a back elevation view thereof;

FIG. 4 is a side elevation view thereof;

FIG. 5 is an opposite side elevation view thereof;

FIG. 6 is a top plan view thereof;

FIG. 7 is a bottom plan view thereof;

FIG. 8 is an upper perspective view of the support structure for a grill showing a grill positioned thereon;

FIG. 9 is a front elevation view of the support structure for a grill showing a grill positioned thereon; and,

FIG. 10 is a front elevation view, of the support structure for a grill, showing a grill positioned thereon, wherein the side trays are folded upwards.

The grill shown in broken lines in FIGS. 8-10 is for environmental purposes only and forms no part of the claimed design.
